R. M. CONKLIN

DISCHARGE CHUTE SHUTTER

Filed March 3, 1922

UNITED STATES PATENT OFFICE.

ROBERT M. CONKLIN, OF JERSEY CITY, NEW JERSEY.

DISCHARGE-CHUTE SHUTTER.

Application filed March 3, 1922. Serial No. 540,769.

To all whom it may concern:

Be it known that I, ROBERT M. CONKLIN, a citizen of the United States, and resident of Jersey City, in the county of Hudson and 5 State of New Jersey, have invented certain new and useful Improvements in Discharge-Chute Shutters, of which the following is a specification.

The invention relates in general to a lever 10 actuated closure and specifically relates to an improved form of shutter or valve for closing the discharge chute in vending apparatus of the type usually employed for measuring and discharging a powder, such as milk 15 powder, and the invention constitutes an addition to the device disclosed in my co-pending application on dispensing devices filed June 6th, 1921, Serial No. 475,191.

In the device disclosed in the above-identified 20 application there was shown a measuring valve positioned at the top of the discharge chute and which valve was provided with a pair of pockets, each designed for receiving and measuring and when rotated 25 for discharging the substance to be vended into the discharge chute. The valve was controlled by a lever which rotated the valve on a down stroke of the lever, and which lever returned idly under spring tension 30 into its raised, initial position.

The lever in such constructions is designed to swing over a relatively long arc so as to obtain from a single, quick, nervous muscular thrust on the part of the operator, sufficient 35 power to actuate the valve under conditions where the valve is apt to stick. The present invention contemplates the utilization of some of this available power to open the chute shutter and accordingly the shutter 40 is operatively connected to the lever. While a long lever movement is necessary to actuate certain types of valves, on the contrary it is desired that the movement of the shutter be confined to the smallest possible 45 range merely sufficient to clear the chute.

Accordingly, one of the objects of the invention is to provide a simple form of connecting means between the lever and shutter for moving the shutter positively over a relatively 50 short distance from its closed into an open position by the initial movement of the lever and independently of the succeeding extent of movement of the lever in its valve actuating movement.

Another object of the invention is to pro-

vide a means controlled by the movement of the shutter into its open position for locking the shutter in such position until the control lever is returned to its initial position.

Still another object of the invention is to 60 provide for a prompt positive and secure closing of the shutter when free of the locking action of the lever controlled connecting means.

Various other objects and advantages of 65 the invention will be in part obvious from an inspection of the accompanying drawings and in part will be more fully set forth in the following particular description of one form of mechanism embodying my invention, 70 and the invention also consists in certain new and novel features of construction and combination of parts hereinafter set forth and claimed.

In the accompanying drawings:—

Figure 1 is a view in side elevation of the lower portion of a vending machine provided with a preferred embodiment of the invention; and

Figure 2 is a vertical sectional view taken 80 on the broken line 2—2 of Figure 1 looking in the direction indicated by the arrow.

In the drawings there is shown a casting 10 which includes a central cylinder valve containing casing 11, into which leads a feed 85 chute 12 and from which leads a discharge chute 13. A rotary valve 14 is positioned in the casing 11 and is mounted for rotary movement upon the shaft 15 which shaft projects into a mechanism containing casting 16 and is operatively connected to be actuated by a hand lever 17 through any suitable form of mechanism including a pawl and ratchet 17' forming no part of this disclosure but one form of which is disclosed in the above identified application. 90 As shown in Figure 1 the lever is pivotally mounted on a pin 52 and is provided with a one-way acting pawl 54 designed to engage with a dual tooth ratchet 41 to move the 95 same 180° with each complete actuation of the lever. The ratchet is secured to one end of the shaft 15. The lever is returned to its normal position by return spring 56.

The valve is provided with two diametrically disposed pockets 18 and 19 and the parts are so organized that a downward thrust of the lever 17 will act idly during the initial part of its swing, in so far as the valve is concerned and will act during the 110

final part of its downward swing to move one of the pockets, such for instance, as the pocket 18 from the upper, substance receiving position, into the lower position occupied by the pocket 19 in Figure 2 and disposed to discharge its contents from the device through the discharge chute 13.

The discharge chute 13 is normally closed by a shutter 20 which is held resiliently against the inclined or bevelled end 21 of the chute by means of a spring 22, which engages a shutter controlling depending arm 23. The lower end of this arm is secured to the shutter 20 and the upper end is pivotally connected to a lug 23^a depending from an extension 24 from the casting 10 and which extension connects the casings 11 and 16 and provides a bearing for the shaft 15.

20 A cam connection is provided between the lever 17 and the shutter 20, which is so organized that the initial movement of the lever in its valve actuating downward stroke will move the shutter from its closed, full-line position into its open, dotted line position shown in Figure 2. This cam connection includes an arcuate plate 25 mounted for swinging movement on the inner side of the casing 16 and is guided in its movement 25 about the axis of the shaft 15 by means of guide pins 26 disposed in a slot 27 formed in the plate 25. The upper end of the plate 25 is provided with a bifurcated end 28 which straddles the lever 17 and is thus moved by the lever in its movement in both directions. The inner edge of the plate 25 adjacent its lower end is provided with an active cam face 29 disposed to engage a stop roller 30 on the arm 23. The downward movement of the cam engages the stop roller 30 to move the shutter into its open position, after which the continued movement of the cam under the progressive action of the lever 17 will cause the cam to pass under the roller and the long locking face 31 of the cam will act on the stop roller to hold the same in the shutter locking and open position shown in dotted lines in Figure 2.

50 In operation it will be understood that the parts are initially in the position shown in full lines in Figure 2 and that the upper valve pocket 18 is filled with powder or other substance fed therethrough through the hopper 12. The initial movement of the 55 valve controlling lever 17 on its downward stroke will be to start the valve rotating clockwise and at the same time open the shutter, so that by the time the upper pocket 18 has reached its lower discharging position the shutter will be fully moved into its 60 open position and will be even locked in this open position. When the operator releases tension on the lever it will tend to return to its upper position with the lever which is 65 spring controlled and during this initial

part of the lever retreat the shutter will be still held in an open position and the shutter will not close until free of the locking effect of the cam. This closing action of the shutter in its return to its closed position, 70 will not take place until the lever is practically returned to its initial position. By this construction it is apparent that the discharge shutter is normally closed when the device is not in operation but will be fully 75 opened before the valve is in position to discharge its contents and will remain open for a time sufficient to permit the discharge of the substance through the chute.

80 While I have shown and described, and have pointed out in the annexed claims, certain novel features of my invention, it will be understood that various omissions, substitutions and changes in the form and details of the device illustrated and in its operation 85 may be made by those skilled in the art without departing from the spirit of the invention.

Having thus described my invention, I claim: 90

1. In a device for discharging a substance, the combination of a chute, valvular mechanism for controlling the discharge through the chute, said mechanism including an actuating lever, a closure for the chute, and means operated by the lever for moving the closure into open position on the initial movement of the lever. 95

2. In a device for discharging a substance, the combination of a chute, mechanism for 100 controlling the discharge through the chute, said mechanism including an actuating lever having a handle movable on its actuating stroke over a relatively long arc, a closure for the chute with its free end movable over 105 a relatively short arc and a cam for translating the long movement of the lever into a short movement of the closure.

3. In a device of the class described, the combination of an actuating lever, a closure pivotally mounted, a cam disposed in the path of the lever and moved thereby when the lever is moved in one direction, said cam having an active face adapted to engage the closure to swing the same about 110 its pivotal mounting. 115

4. In a device of the class described, the combination of an actuating lever, a closure pivotally mounted, a cam disposed in the path of the lever and moved thereby when the lever is moved in one direction, said cam having an active face adapted to engage the closure to swing the same about 120 its pivotal mounting and said cam provided with a locking face forming a continuation 125 of the active face and adapted to lock the closure in open position as the lever is advanced in said direction.

5. In a device of the class described, the combination of an actuating lever, a closure, 130

and cam means therebetween for causing said lever in its movement in one direction to have in succession an engagement with the closure to swing the same into an open 5 position and then an engagement to lock the closure in said open position.

6. In a device of the class described, the combination of an actuating lever, a closure, and cam means therebetween for causing said lever in its movement in one direction to have in succession an engagement with the closure to swing the same into an open position and then an engagement to lock the closure in said open position, 10 said closure adapted to return to its closing position when free of the lever controlled cam means.

7. In a device of the class described, the combination of a support, a depending arm 20 hung from the support, a closure carried by the arm and a stop roller carried by the arm, a cam having an active face connected to the lever to move therewith and said active face adapted to engage the stop to 30 swing and lock the closure in open position.

8. In a device of the class described, the combination of a valve and a shutter, an actuating lever for controlling the valve and 35 means controlled by the lever and having a timed relation to the valve whereby the shutter is moved into open position on the initial movement of the valve.

9. In a device of the class described, the combination of a valve and a shutter, an actuating lever for controlling the valve, means controlled by the lever and having a timed relation to the valve whereby the shutter is moved into open position on the 5 initial movement of the valve, and means for locking the shutter in open position

operatively connected to secure the shutter during the final movement of the valve.

10. In a device of the class described, the combination of a shutter having a relatively short opening movement, a lever having a relatively long actuating movement and connecting means between the lever and shutter, said connecting means having an idling movement under the continued action 45 of the lever following the short movement of the shutter into its open position.

11. In a device of the class described, the combination of a shutter having a relatively short opening movement, a lever having a relatively long actuating movement, connecting means between the lever and shutter, said connecting means having an idling movement under the continued action 50 of the lever following the short movement of the shutter into its open position and resilient means for returning the connecting means idly towards its initial position.

12. In a device of the class described, the combination of a shutter having a relatively short opening movement, a lever having a relatively long actuating movement, connecting means between the lever and shutter, said connecting means having an idling 55 movement under the continued action of the lever following the short movement of the shutter into its open position, resilient means for returning the connecting means idly towards its initial position and resilient means 60 acting on the shutter for moving the same into its closing position when free of said connecting means.

Signed at New York in the county of New York and State of New York this 17th 65 day of February, A. D. 1922.

ROBERT M. CONKLIN.
